UNITED STATES PATENT OFFICE.

JOHN MACNAULL WILSON, OF NEWARK, NEW JERSEY, ASSIGNEE TO FRANKLIN MURPHY, OF NEWARK, NEW JERSEY.

PROCESS OF RENOVATING CANE SEATS.

1,243,474.

Specification of Letters Patent. Patented Oct. 16, 1917.

Application filed June 24, 1914, Serial No. 846,913. Renewed March 2, 1917. Serial No. 153,457.

To all whom it may concern:

Be it known that I, JOHN MACNAULL WILSON, a citizen of the United States, and resident of Newark, in the county of Essex and State of New Jersey, have invented certain new and useful Improvements in Processes of Renovating Cane Seats, of which the following is a specification.

My invention relates to a process and apparatus for bleaching and renewing materials of vegetable fiber, such as articles made of straw, cane and similar materials and relates particularly to the treatment of articles such as car seats made of woven strips of cane.

Heretofore in treating articles of the class described, it has been customary first to subject the article to a preliminary scrubbing or brushing or to the action of a vacuum cleaner in order to remove loose particles of dirt or dust which may adhere to the car seat. The seat is then dipped in a vat of cleansing liquid which is permitted to soak into the material in order to soften the shellac or varnish with which the seat has been finished. Necessarily, this liquid is corrosive in character and very detrimental to the springs and other metal parts used in the construction of the seat. It is also harmful to the cane, since it gains access to the inner and untreated surface of the cane and thus penetrates and soaks into the cane. The seat is then scrubbed or brushed manually to remove the shellac or varnish that may have penetrated the cane. Following this, the seat is rinsed in water and is then allowed to drain, usually for a number of hours. Finally, the seat is placed in a drying room in order that it may become thoroughly dry preparatory to being re-stained or revarnished as the case may be, the whole operation as last described requiring two or three days.

According to my improved process, the seat or cushion is cleaned, the stains and a uniform quantity of the shellac or varnish is removed and the cane bleached and practically dried so that the seat is ready to receive a finishing coat of shellac or varnish in a practically continuous operation, requiring but a few minutes of time, without soaking the cane or other material, and without subjecting the springs or other

metal parts to the action of any corrosive or other liquid whatever.

55

In carrying out my improved process, the liquid which removes the stains, grease and foreign matter, together with a sufficient portion of the shellac or varnish, if present, to give the seat a uniform appearance when bleached, is preferably applied to the surface of an inverted seat in the form of a spray forming a practically uniform film over the surface without penetrating into the pores of the material. If desired, the seat may be subjected to a preliminary brushing or scrubbing by means of a suitable brush, although such preliminary step is seldom necessary because the loose dirt and dust is removed, together with the renovating liquid. Almost immediately after the spray of liquid has been applied to the surface, it is subjected to the action of a friction device operating at high speed, preferably a brush comprising relatively stiff bristles or fine soft wire and rotating at a speed upward of two thousand revolutions per minute, whereby an extremely rapid and vigorous scrubbing action is exerted against the material, not only on the overlapping portions of the weave, but also on the depressed portions thereof. The seat or other article being treated is alternately subjected to the action of the brush and liquid spray, and then to the brush alone until all of the renovating fluid has been removed and the surface is practically dry. Thereupon the seat receives a bleaching liquid, which preferably is applied by means of a rotating brush having its bristles continuously moistened by any suitable means as a spray arranged adjacent to the surface thereof. The bristles of this brush are sufficiently soft to apply the bleach uniformly over the entire surface, and owing to the fact that the seat has just been cleaned, the bleach is readily distributed and absorbed. After a sufficient quantity of bleach has been applied, the brush is then sprayed with water or other liquid to remove or neutralize any excess of the bleach. As soon as this result has been accomplished, the water is turned off and the seat is subjected to the same action for a slightly longer period until it is practically dry. The drying requires a comparatively short

time, as the brush is rotated at a relatively high speed.

In the accompanying drawings, I have shown one form of apparatus for carrying out my improved process, in which

5 Figure 1 represents a plan view of the machine;

10 Fig. 2 represents an end view of the machine, and

15 Fig. 3 represents a side elevation thereof.

In said apparatus, the frame 1 is provided with a plurality of brushes 2 so that the tops thereof project a predetermined distance above the level of the frame. A 20 plurality of rollers 3 are also supported on the top of the frame, said rollers being of a predetermined size relative to the diameter of the brush so that any article resting upon the rollers will be caused to engage with the bristles of the brush. The 25 rollers are arranged at suitable intervals with relation to each other to permit reciprocation of the seat or the article being treated with respect to each of the brushes, if desired.

30 Adjacent to each of the rollers are one or more nozzles or outlets whereby a liquid may be supplied either to the surface under treatment in the form of a spray or directly upon the brush. Preferably each brush is provided with a nozzle 4 and a spray pipe 5. The nozzles and spray pipes are connected with suitable reservoirs or supply tanks 6 permitting the liquid contained 35 therein to be placed under pressure. The quantity of liquid supplied to the spray pipes or nozzles is controlled in any suitable manner, as by the valves 7.

40 The brushes are driven at a high speed of rotation in any suitable manner, as by the belts 8 and the pulleys 9. It is obvious, however, that any other form of high speed driving means may be employed if desired.

45 In order to treat seats of considerable length, I provide special means, as shown in Fig. 1, whereby the whole length of the seat may be treated by one brush before being subjected to the action of the second. Referring to Fig. 1, the frame is provided 50 with transverse rollers 10 having their axes perpendicular to the axes of the brushes. A suitable arm or bracket may be provided on the frame or a separate support may be provided for that portion of the seat which 55 extends beyond the edges of the frame. The seat is reciprocated transversely to the frame but parallel to the face of the brush until the treatment with respect to said brush is fully completed.

60 By means of this construction, the bleaching of any article such as a cane seat and the treatment preparatory to such bleaching can be carried out and completed on a single machine in a comparatively short space 65 of time, constituting practically a contin-

uous operation. In practice, the seat is placed upside down on the rollers so that its outer or wearing surface will contact with the brush. This prevents any liquid that may be applied from seeping through or 70 coming into contact with the interior of the seat. This position also permits the rinsing water to be applied rapidly and in considerable quantity, since any excess drops downward from the surface. In certain cases, 75 the cleaning liquid and the bleach may be placed in the same receiver or reservoir and applied to the seat in one operation. It is obvious of course, that the several steps of the process may be employed upon totally 80 distinct and separate machines and by various forms of apparatus other than the particular apparatus herein set forth and described.

85 Although I have described my improved process and apparatus particularly with respect to cane seats such as are used in railway cars, it will be evident that any similar articles may be treated in like manner with similar results, and that various 90 changes and modifications, both in the process and apparatus, within the knowledge of those skilled in the art, may be made without departing from the spirit of the invention, provided the means set forth in the 95 following claims be employed.

I claim as my invention:—

1. The process of treating cane seats which consists in supplying a renovating liquid thereto in the form of spray to cause 10 a film of the renovating liquid to be deposited on the surface, subjecting said surface to the action of a rapidly revolving brush simultaneously to scrub the surface and remove the liquid therefrom, drying 10 said surface by continuous application of the brush, applying a bleaching liquid to said surface by means of a rapidly rotating brush moistened with the bleaching liquid, then neutralizing the bleaching solution and 11 drying the surface.

2. The process of bleaching and renewing surfaces containing vegetable fiber which consists in supplying a corrosive liquid thereto in the form of a film deposited on 11 the surface, subjecting said surface to the action of a rapidly revolving brush while the liquid is being supplied, continuing treatment by the brush after the supply of liquid has been discontinued to remove excess liquid, and then neutralizing the action of the remaining corrosive liquid by applying a non-corrosive liquid to the surface without permitting penetration of such liquid beneath the surface of the seat. 12

3. The process of bleaching and renewing surfaces containing vegetable fiber which consists in supplying a corrosive liquid thereto in the form of a film deposited on the inverted surface of the article 13

being treated, subjecting said inverted surface to the action of a rapidly revolving brush to remove a portion of the liquid therefrom, partially drying said surface and then applying a non-corrosive liquid to said surface by means of a rapidly rotating brush and then drying said surface.

Signed at Newark in the county of Essex and State of New Jersey this eighteenth day of June A. D. 1914.

JOHN MACNAULL WILSON.
